UNITED STATES PATENT OFFICE.

RALPH C. SIMMONS, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL-ATTACHING MACHINE.

1,366,964.

Specification of Letters Patent.

Patented Feb. 1, 1921.

Application filed December 3, 1917. Serial No. 205,094.

To all whom it may concern:

Be it known that I, RALPH C. SIMMONS, a citizen of the United States, residing at Beverly, in the county of Essex and State of Massachusetts, have invented certain Improvements in Heel-Attaching Machines, of which the following description, in connection with the accompanying drawings, is a specification, like reference characters on 10 the drawings indicating like parts in the several figures.

This invention relates to heel attaching machines and more particularly to that type of machine which is adapted for use in attaching heels to boots or shoes by means of 15 nails or similar fastenings driven into the heel from the inside of the shoe.

Heel attaching by fastenings driven from the inside of the shoe through the insole and 20 outsole into the heel, commonly called "inside nailing," is practised to a large extent with so-called Louis or ogee heels which have a large heel seat surface and a very small cross-section at the waist. Such heels 25 have a great deal of pitch or overhang at the rear, and for this reason present certain difficulties to solid and secure attachment. It is particularly important that a heel of 30 this type be strongly attached to the shoe as close as possible to its rear end, since the tread face of the heel is set well forward and a tremendous leverage is thus exerted by the weight of the wearer tending to separate 35 the rear end of the heel from the shoe.

The ordinary method of attaching an inside nailed heel by nails driven substantially normal to its seat surface is more or less inadequate in the case of heels having considerable pitch, since the rearmost nail must 40 be driven a considerable distance from the rear end of the heel in order to prevent its point from emerging through the heel surface. In order to permit the rearmost nail to be driven nearer the rear end of the heel, 45 it has been proposed to drive it in an inclined direction, whereby its point is kept well within the heel body, while it enters the heel nearer the rear end of the latter where the greatest holding power is needed. 50 It has even been proposed to provide a heel attaching machine with an inclined nail driver for this purpose, but such drivers have been moved in a straight line, and consequently, inasmuch as they must work inside 55 the shoe, the approach of the nail to the

rear of the heel has been limited by the counter and upper.

An important object of the present invention is to provide a nailing machine for inclined nailing which will permit the insertion of a nail into the work at a point nearer the limiting boundary of the work than is possible with the machines heretofore known. In its application to the art of inside heel nailing, the desirable result is attained that a nail may be driven closer to the rear of the heel than heretofore, and the heel thus be more securely attached at this vital point.

In pursuance of the object above outlined, I have succeeded in greatly improving nailing mechanism of the type referred to by the employment of a curved nail driver guided for movement in a correspondingly curved path. I am thus enabled to drive 75 a heel nail at an inclination to the surface which it enters and so to arrange the driving mechanism that the nail will enter the work much closer to the limiting boundary thereof than if a straight driver were used. 80 In inside heel nailing, it is practicable, by the use of mechanism embodying my invention, to drive a heel attaching nail quite close to the rear of the heel, inasmuch as the shape and the path of the driver may be of 85 a curve approximating, more or less, the shape of the inside of the rear portion of the shoe.

In a preferred form of the invention, the nail driver is curved in an approximately 90 circular arc and in its movement is guided by a suitable correspondingly shaped arcuate driver passage.

A further object of the invention is to provide improved means for adjusting the 95 effective length of the drivers in nailing machines where the precise depth to which the nail is set in the work is a matter of importance. Although its utility is not limited to such conditions, a construction embodying the present invention is particularly useful and convenient in cases where the nail driver is incased or not easily accessible from the side. It has been proposed in the past to provide for simultaneous adjustment 105 of all the drivers of a gang by means of a laterally movable wedge underlying the driver plate and operated from one side. By my invention, I have provided for greater refinement of adjustment, in that 110

I have arranged for independent adjustment of the individual drivers and, in a preferred embodiment of the invention, this adjustment may easily and conveniently be effected 5 without gaining access to the drivers or their supporting plate laterally.

One way in which I have in practice secured the results above indicated consists in the provision of a driver having threaded 10 engagement with its supporting block or member, and so formed at its other end that it may be engaged and turned in or out of its support by a tool inserted in the open end of the nail and driver guiding passage 15 in the nail block or its equivalent. This formation may conveniently consist of a slot in the advance end of the driver which may be engaged by a screw driver inserted in the guide passage. Where there are a plurality 20 of drivers constructed as just described, the effective length of each driver may be adjusted independently of all the others.

For the purpose of disclosing the invention, I have selected a practical embodiment 25 thereof which I shall now proceed to describe in detail, making reference to the accompanying drawings, in which

Figure 1 is a vertical sectional view of a portion of a heel nailing machine embodying 30 my invention, showing a portion of a shoe supported in coöperative relation thereto;

Fig. 2 is a perspective view of a detail of the nail driving mechanism;

Fig. 3 is a plan view of part of the mechanism shown in Fig. 1 with the shoe removed;

Fig. 4 is a view of a securing member for maintaining the driver guide in position; and

Fig. 5 is a view of an adjustable driver and its mounting.

For an illustrative embodiment of the invention I have shown it applied to a well known wood heel nailing machine of the 45 type shown in United States Letters Patent 1,269,654, granted June 18, 1918, upon the application of John F. Standish, to which reference may be had for a description of features of construction of such a machine 50 which are not directly related to my invention.

Referring now to the drawings, 10 indicates the work support or jack of a heel nailing machine and 12, 14 indicate the usual devices for pressing a heel upon a shoe and holding it in position while it is being attached. The upper end of the jack 12 carries a plate 16 in which are adjustably mounted driver tubes 18 guiding straight nail drivers 20. The plate 16 is slotted at 22 and a driver guide, indicated generally by 24, is formed to fit the slot. A flange 26, formed upon the driver guide rests on top of the plate 16, supporting the driver guide in operative 60 position. The driver guide is formed of two

complementary sections 28, 30 designed to be secured together by screws 32. An arcuate driver guiding passage 34 is formed in the guiding member 24, and a correspondingly curved driver 36 is guided for movement in the said passage. A spring 38, held in a slot 40 in the guide section 28, tends, by the engagement of its free end in an opening 42 in the end of the driver 36, to hold the driver in retracted position. The opposite end of the spring is bent up, as shown at 44, and acts as a stop to limit the retracting movement of the driver, by reason of the engagement with the bent up end 44 of the spring of a shoulder 46 formed upon the driver. 80 The lower end of the driver guide is slotted at 48 to permit the entrance of a flat plate 50 which is mounted upon the upper end of a reciprocable plunger 52. The elements just described are so related that when the 85 plunger 52 is elevated the upper end of the plate 50 engages the lower end of the driver and advances the driver longitudinally to drive the nail, the plate 50 entering the slot 48 in the latter part of its upward movement.

In the actuation of a curved driver of the sort herein illustrated, there is a very considerable horizontal component in the force transmitted to it, and difficulty has been experienced in securing the driver guide 24 in adjusted position in the slot 22. For the purpose of permitting adjustment of the driver guide longitudinally of the shoe and securing the guide immovably in adjusted position, I have provided the following construction. A series of recesses 54 are formed in the edge of one of the flanges 26, and a pin 56 of a size suitable for engagement in one of the recesses is set rigidly into the 105 plate 16. The driver guide may be lifted sufficiently to disengage the flange 26 from the pin 56, whereupon the driver guide may be moved forwardly or rearwardly to the desired position, and the flange again seated upon the plate 16 with the pin 56 in the appropriate recess 54. A cap 58, provided with an opening 60 to accommodate the nozzle of the driver guide, is then placed upon the flange 26 and secured by screws 62 engaging threaded holes 64 in the jack top. 110 With this construction the driver guide may readily be adjusted to any required position longitudinally of the heel and may then be secured against any possibility of movement.

The driver 36 is of rectangular cross-section and the guiding passage in the driver guide is of a corresponding shape, with the exception of the upper end, where a portion 125 of the passage is drilled out into a circular shape of a size suitable for the head of the attaching nail to be used and a depth sufficient to include the length of the nail, as shown at 65. In Fig. 1 the nail is indicated 130

in dotted lines resting in the round opening in the upper end of the driver guide in position to be driven, while the full lines at 66 indicate the nail as it is actually driven 5 into the work. Before driving the nail, the shoe occupies such a position on the jack that the rear portion of the upper is drawn snugly against the back of the jack. Inasmuch as the point of the nail, as shown in 10 dotted lines in Fig. 1, lies slightly forward of the point where the head of the nail must leave the bore 65, the shoe must move slightly to the rear relatively to the jack while the nail is being driven. There is 15 sufficient spring or yield in the jack and heel support 14 to permit this, and the operation is probably aided by some springing of the nail itself. In any event, it has been found that the nail is driven successfully and that 20 it has greater holding power than when driven in the way which has heretofore been customary.

The upper end of the driver 36 is narrowed, as shown at 38, the object being to 25 permit the nail head to be sunk into the insole until it is flush or below the surface thereof without making an unnecessarily large defacing mark in the sole.

Referring now to Fig. 5, the lower end 30 of the straight driver 20 is threaded at 70 and is screwed into a suitably formed block 72 which rests upon the reciprocable plunger head 74, being retained in operative relation thereto by the plate 76 which is slotted 35 to permit transverse adjustment of the driver. The block 72 is split part way through, as shown at 78, and the two sides sprung together to cause the threaded end 40 of the driver to fit tightly, in order that there may be no danger of its turning accidentally and varying the adjustment.

The upper end of the driver is slotted at 80, and a screw driver 82 or other suitable implement may be inserted in the top of the 45 guide 18 to turn the driver 20 to adjust it up or down, as conditions may require.

Having described my invention, what I claim as new and desire to secure by Letters Patent of the United States is:—

50 1. An inside nailing heel attaching machine comprising a work support constructed and arranged to enter the heel end of a shoe, coöperating pressing means for holding a heel upon the shoe while it is being attached, a curved driver guide mounted in the work support with its exit portion at an inclination to the surface of the work upon the support, a curved, reciprocable nail driver contained in the guide, and means for advancing the driver until its point engages the shoe, whereby a heel attaching nail may be completely driven in an inclined direction from the inside of the shoe with a single stroke of the driver.

65 2. An inside nailing heel attaching ma-

chine having means for driving a nail at an inclination to the surface of the work at which it enters, comprising a work engaging member constructed and arranged to enter the heel end of a shoe, a nail and driver 70 guiding member having a curved guide passage therein mounted in the work engaging member, and a curved nail driver reciprocable in said passage and guided solely thereby. 75

3. A nailing machine having means for driving a nail at an inclination to the surface of the work at which it enters, comprising a nail and driver guiding member having a curved guide passage therein, a 80 curved nail driver in said guide passage and guided solely thereby, and rectilinearly movable means for imparting sufficient longitudinal movement to the driver to drive a nail completely out of the guide passage. 85

4. A nailing machine having means for driving a nail at an inclination to the surface of the work at which it enters comprising a nail and driver guiding member having a curved guide passage therein, a curved 90 nail driver reciprocable in said passage and guided solely thereby, and an actuator for advancing the driver to drive a nail.

5. In a machine of the class described, a nail and driver guide having a curved driver 95 guiding passage and a straight nail guiding passage of a length at least equal to that of the nail to be driven.

6. In a machine of the class described, the combination of a driver supporting device, 100 and a nail driver having threaded engagement with the supporting device, one end of the driver being formed to coöperate with a tool, whereby the effective length of the driver may be adjusted by turning into or 105 out of its support.

7. In a machine of the class described, the combination of a driver supporting device, and a nail driver one end of which is threaded into the supporting device and the other 110 end of which is formed for interlocking engagement with a tool for turning the driver.

8. In a machine of the class described, the combination of a driver supporting device, and a nail driver one end of which has 115 threaded engagement with the supporting device and the other end of which is provided with a screw driver slot.

9. In a machine of the class described, the combination of a driver and a driver support into which the driver is adjustably threaded, said support comprising a block split and sprung together to grip the threaded end of the driver tightly, to insure the preservation of the adjustment. 120

10. In a machine of the class described, the combination of a driver support, a driver guide, and a nail driver threaded into said support and having a transversely slotted nail engaging end in said guide. 125

11. In a machine of the class described, the combination of a plurality of independent driver supports and a nail driver having threaded engagement with each of said supports, the supports and the drivers held thereby being adjustable transversely toward and from each other and each driver being adjustable in its support to vary its effective length.
- 10 12. In a machine for attaching a heel to a shoe, the combination of a curved nail

driver, means for guiding the driver for movement in a curved path, said guiding means with its contained driver being adjustable in position longitudinally of the heel, and means for actuating the driver to drive a heel attaching nail in any position of adjustment of said guide.

In testimony whereof I have signed my name to this specification.

RALPH C. SIMMONS.
